CENTRIFUGAL ATOMIZER

David D. Peebles, Hillsborough, and Clarence P. Turner, Petaluma, Calif., assignors to Western Condensing Company, San Francisco, Calif., a corporation of California

Application January 16, 1951, Serial No. 206,162

3 Claims. (Cl. 299—63)

1

This invention relates generally to centrifugal atomizers and atomizing methods suitable for use with spray driers.

Centrifugal atomizing devices for spray driers generally employ an atomizing head mounted upon a shaft and rotated at a relatively high rate of speed. The material to be atomized is fed to the head and as it is thrown outwardly by centrifugal force, it is acted upon by atomizing means such as a plurality of circumferentially spaced impact bars. A centrifugal atomizer of this type has undesirable features, particularly when used for certain types of service. For example, there is a tendency toward lack of uniformity of the particle size of the atomized material, and the average size of the particles may be larger than is desirable in the spray drying of many products. There is also a tendency for such atomizers to discharge coarser particles at relatively high tangential velocity, with the result that such particles tend to directly impact the side walls of the desiccating chamber, rather than to be entrained in the drying gas. In addition to the disadvantages just mentioned there is a tendency for the circumferentially spaced impact bars to be subject to excessive wear.

It is an object of the present invention to provide a centrifugal atomizer and method which will overcome the difficulties pointed out above.

Another object of the invention is to provide an atomizer and method capable of relatively fine and uniform atomization of various fluid feed materials, and which will facilitate entrainment of the atomized material in drying gas.

Another object of the invention is to provide an atomizing device and method which will avoid the use of impact bars or like mechanical impacting means for effecting a substantial amount of atomization.

Additional objects of the invention will appear from the following description in which the preferred embodiment has been set forth in detail in conjunction with the accompanying drawing.

Referring to the drawing:

Figure 1 is a side elevational view in section illustrating an atomizing device incorporating the present invention.

Figure 2 is a cross-sectional detail taken along the line 2—2 of Figure 1.

Figure 3 is a cross-sectional detail taken along the line 3—3 of Figure 1.

Figure 4 is a detail looking toward one peripheral surface of the atomizing head.

2

Figure 5 is a detail serving to diagrammatically illustrate the method.

The atomizing device illustrated in the drawing consists generally of an atomizing head 10 which is circular in contour, and which is attached to the rotatable shaft 11. In the particular construction illustrated the shaft is made hollow and in two coupled sections 11a and 11b. The mounting means for journaling this shaft 10 may consist of the ball bearing assemblies 12 and 13, which are carried by the mounting rings 16 and 17. These rings are connected by the concentric tubes 18, 19, which are dimensioned to provide a space 21 for circulating cooling liquid. The upper mounting ring 16 can be attached to the top wall (not shown) of a desiccating chamber. The shaft is shown being driven by suitable means such as the pulley 22.

A feed tube 26 extends downwardly through the longitudinal shaft passage 27. The upper end of this tube is carried by the support bracket 28. At one point along its length the tube is steadied by the ball bearing assembly 29. As illustrated it is desirable for the feed tube 26 to have a small spacing or clearance with respect to the surrounding shaft.

The atomizer head consists of a hub 31 which carries the disc-like plates 32 and 33. The lower plate 33 is secured to the hub by suitable means such as the dowels 34 and the locking nut 36. The inner periphery of the upper plate 32 is shown seated upon the annular shoulder 37 formed on the hub. The two plates are clamped together by suitable means such as the circumferentially spaced screws 38.

The hub 31 is bored to provide the annular chamber 39, and a plurality of openings 41 in the lower end portion of the shaft serve to connect this chamber with the lower portion 42 of the passage 27 through the vertical drive shaft. Another series of circumferentially spaced openings 43 are formed in the hub and serve to deliver material from the annular chamber 39 into the space 44 between the plates 32 and 33. The openings 43 are regularly spaced about the hub (see Figures 1 and 2) to secure uniform distribution of material into the space 44.

The peripheral margin of the lower plate 33 is formed to provide a plurality of circumferentially spaced slots 46. These slots extend in a general radial direction, although as illustrated in Figure 3 it is desirable that they be at a small angle to radii from the center of rotation. In the specific proportioning illustrated this angle is 5°, and the outer end of each slot is offset toward the direction of rotation.

Slots 46 are preferably of uniform width as measured in a circumferential direction, and they are substantially rectangular in cross-sectional contour. The ribs 47 which intervene between the slots are slightly tapered, as viewed in Figure 3. The bottoms of the slots, indicated by the dotted line 48 in Figure 1, are preferably coincident with a plane at right angles to the axis of rotation. As viewed in Figure 1 each rib 47 is formed of two portions 47a and 47b. The portion 47a is of uniform height, whereas the portion 47b is of gradually reduced height to terminate at 49 flush with the adjacent face 51 of the plate 33.

The lower face of the upper plate 32 is slotted in a manner similar to the lower plate 33. Thus the outer margin of the upper plate 32 is provided with the rectangularly contoured slots 52, which are separated by the circumferentially spaced intervening ribs 53. The bottoms of the slots are coincident with the surface 54, which is planar and parallel to surface 48. The two portions 53a and 53b of the ribs 53 correspond to and are shaped like the rib portions 47a and 47b previously described.

When the two plates 32 and 33 are assembled as in Figure 1, adjacent slots of the two plates are substantially parallel and they are staggered as illustrated in Figure 4. Thus each slot is closed by the adjacent rib of the opposed plate. Such closed slots form elongated passages which communicate at their inner ends with the space 44 within the head, and which at their outer ends communicate with the peripheral surface 56 of the head. Each of these passages is closed for the radial distance a (Figure 3) and inwardly from this region the passages communicate with the space 44. For the region b (Figure 3) the rib portions 53b and 47b are divergent, and serve as vanes to impart rotary velocity to fluid feed material, and to aid uniform distribution of the feed material into the various passages.

Operation of the atomizer, and the present method, can be described as follows: The drive shaft is usually mounted in a vertical position with the mounting ring 16 being attached to the top wall of a desiccating chamber. The pulley 22 is connected to drive means whereby the shaft is driven at a speed which will provide a suitable peripheral velocity, such as from 450 to 650 feet per second. A source of fluid feed material to be atomized is coupled to the upper end of the pipe 26. Feed material continuously delivered through the pipe 26 is introduced into the lower end portion 42 of the shaft passage, and from thence it is discharged through the openings 41 into the hub chamber 39. From chamber 39 the material is discharged through the openings 43 into the space 44 of the rotating atomizer head. As discharged outwardly through the space 44 the streams of material break into the form of a coarse spray which is uniformly distributed about the space 44. As the coarse spray reaches the region of the rib portions 53b and 47b it is acted upon by these ribs whereby its rotary velocity is increased and where it is distributed into the several slots or passages 46. As the material progresses outwardly through these passages, it is pressed against the side surfaces of each passage to cause the effect of a substantially compact outwardly flowing film. This flowing film effect takes place upon the side surfaces 76, 77 (Figure 4) of the slots or passages 46, 52, assuming the direction of rotation is as indicated. In other words it takes place upon the trailing

rather than the leading side surfaces of the passages. This effect is aided by the angular positioning of the passages illustrated in Figure 3.

All of the fluid feed material is caused to form a flowing film in the manner described above, and no substantial amount of material is permitted to discharge through the passages 46, 52, in the form of particles in free flight. As the feed material enters the zone of the rib portions 53b, 47b some atomization may take place by mechanical impact, but such atomized particles are not permitted to have free flight through the passages for discharge from the atomizer head. On the contrary while passing through the radially extending passages 46, 52, such particles are necessarily caused to merge with the flowing film described above, whereby substantially all of the feed material is delivered to the peripheral surface 56 as a composite rapidly moving film.

At the peripheral surface 56 the outwardly moving films of feed material are continuously atomized due to disruptive shearing off and mechanical disintegration as the films meet the surrounding air. Such atomization provides particles of relatively small and uniform particle size.

The method described above is illustrated diagrammatically in Figure 5. The outwardly flowing film of feed material is indicated diagrammatically at 78. The thickness of the film decreases outwardly due to the progressively greater flow velocity. Disintegration and atomization of the film takes place along the vertical edge 79 which is coincident with the peripheral surface 56.

By way of example, in one particular instance the head was 20 inches in diameter, and was operated at a speed of 7,000 R. P. M. The slots were $\frac{1}{8}$ inch in circumferential width, $\frac{1}{16}$ inch deep, and the dimensions a and b were $1\frac{1}{2}$ and $2\frac{1}{4}$ inches, respectively. Such a head operated to secure uniform fine atomization of skim milk, and was employed with a spray drying chamber.

It will be evident from the foregoing that the present atomizer operates entirely by virtue of disintegration of an outwardly flowing film of the feed material. No droplets of material produced by impact disintegration are discharged from the head. Because of the absence of impact disintegration wear of the ribs and the other parts of the atomizer is reduced to a minimum.

We claim:

1. A centrifugal atomizing head comprising a pair of disc-like plates, a hub serving to carry said plates, means for clamping the plates into face to face relationship, means for feeding material into the interior of the hub, said plates having their opposed faces formed to provide an annular space communicating through spaced ports with the interior of the hub, whereby said space receives a coarse spray from the hub when the head rotates, circumferentially spaced ribs formed on the inner face of at least one of said plates and extending from the periphery of the same toward said hub, said ribs serving to form substantially rectilinear passages between the same for passage of feed material, the inner end portions of said ribs being tapered inwardly and spaced from the opposed face of the other plate to form vanes, the other portions of the ribs being in contact with the other plate for a substantial radial distance.

2. In a centrifugal atomizer, a circularly contoured head comprising a pair of disc-like plates, a hub to which the plates are secured, a rotat-

able shaft serving to mount the hub and having its axis coincident with the center of the head, circumferentially spaced slots formed in the opposed peripheral margins of the plates and extending in a general radial direction, the slots of said plates being in staggered relation whereby the slots of one plate are angularly displaced and offset with respect to the slots of the other plate, said slots forming a plurality of enclosed passages having their outer ends terminating with the peripheral surface of the head and having their inner ends communicating with the interior of the head, said passages being of substantial radial length compared to their circumferential dimensioning, a feed chamber formed within the hub and adapted to receive fluid material, said head being formed to provide a space surrounding the hub and communicating with the inner ends of the passages, and the peripheral wall of said hub being provided with spaced openings for discharge of a coarse spray of said material from said chamber into said space, and means for delivering material into the feed chamber.

3. A centrifugal atomizing head as in claim 1

in which said ribs are formed on the inner opposed surfaces of both said plates, the opposed end faces of said ribs being in contact, the slots formed between said ribs being in staggered relation whereby the slots of one plate are angularly displaced and offset with respect to the slots of the other plate.
